United States Patent

Des. 236,977
Patented Sept. 30, 1975

236,977

WRITING INSTRUMENT

Robert Hocq, Boulogne, France, assignor to Interlight

Filed Jan. 21, 1974, Ser. No. 434,995

Claims priority, application France June 23, 1973

Term of patent 14 years

Int. Cl. D19—06

U.S. Cl. D19—51

Fig. 4

Fig. 8 Fig. 1 Fig. 2 Fig. 3 Fig. 6 Fig. 7

Fig. 5

FIG. 1 is a perspective view of a writing instrument showing my new design;

FIG. 2 is a front elevational view with the writing instrument and its cap shown in an exploded relationship;

FIG. 3 is a front elevational view thereof in a closed condition;

FIG. 4 is a bottom plan view;

FIG. 5 is a top plan view;

FIG. 6 is a left side elevational view thereof;

FIG. 7 is a left side elevational view wherein the clip is shown in an extended position; and

FIG. 8 is a rear elevational view.

I claim:

The ornamental design for a writing instrument, as shown and described.
